UNITED STATES PATENT OFFICE.

HARRY N. FEDER, OF WASHINGTON, DISTRICT OF COLUMBIA, ASSIGNOR OF
ONE-HALF TO SAMUEL BENLISA, OF JACKSONVILLE, FLORIDA.

DESIGN FOR AN INKSTAND.

SPECIFICATION forming part of Design No. 22,084, dated December 27, 1892.

Application filed October 18, 1892. Serial No. 449,289. Term of patent 14 years.

To all whom it may concern:

Be it known that I, HARRY N. FEDER, a citizen of the United States, residing at Washington, in the District of Columbia, have invented and produced a new and original Design for Inkstands; and I do declare the following to be a full, clear, and exact description of the same, reference being had to the accompanying drawing, forming a part thereof, in which the figure is a perspective view of the design.

The design consists in an inkstand having a substantially rectangular shape, with perpendicular sides provided with the oblong panels E, the inner part of said inkstand being divided up into compartments.

In the drawing, which represents a perspective view of the inkstand, A indicates the ink-

stand which is substantially rectangular in shape and has its inner part or face A' divided off into the oblong compartments or receptacles 1, 2, 3 and 4.

B is a raised circular rim or partition.

B' B' are ink bottles.

On the upper edge of each of the perpendicular sides D is placed a panel E of oblong form or shape substantially as shown.

What I claim is

The design for an inkstand substantially as herein shown and described.

In testimony whereof I affix my signature in presence of two witnesses.

HARRY N. FEDER.
